UNITED STATES PATENT OFFICE.

ALFRED GRIEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

ARTICLE-ATTACHING MACHINE.

1,413,477.

Specification of Letters Patent. Patented Apr. 18, 1922.

Application filed May 28, 1920. Serial No. 384,795.

To all whom it may concern:

Be it known that I, ALFRED GRIEB, a citizen of the United States, residing at Elizabeth, in the county of Union and State 5 of New Jersey, have invented certain new and useful Improvements in Article-Attaching Machines, of which the following is a specification, reference being had therein to the accompanying drawings.

10 This invention relates generally to machines for attaching articles to fabrics and more particularly to machines for sewing on small articles, such as patches, reinforces or labels.

15 Heretofore, it has been the usual practice to sew the labels to the upper side of the work and, in order to properly hold a label in sewing position, an upper two-part telescopic presser-foot was generally used; the 20 outer part having a narrow inwardly directed ledge at its lower end against which the marginal portions of the label were clamped by the inner part of the presser-foot. This presser-foot, with the label in 25 place therein, obstructs the view of the work to a certain extent, and for this reason, among others, it has been proposed to support the article at the under side of the work so that the upper presser member may serve as 30 a sight and thus assist the operator in accurately locating the work in sewing position.

The feeding of individual articles to sewing position at the under side of the work has heretofore been done by hand but such 35 hand-feeding limits production.

The present invention has for an object to provide automatic mechanism for feeding individual articles to sewing position at the under side of the work.

40 A further object of the invention is to provide the mechanism in such form that, in case of thread breakage, the sewing operation may be repeated without disarrangement of the parts of the machine or displacement of the article from sewing position.

Still further, the invention has for an object to provide the mechanism in a form which requires no cams or main actuating devices other than the usual feed-cams commonly used on article-attaching sewing machines for moving the work relative to the sewing mechanism.

Further objects of the invention will appear from the following description and claims.

To the attainment of the ends in view, the invention in a preferred embodiment is applied to a sewing machine of the well known Singer button-sewer type represented in the United States patent to J. J. Sullivan, No. 60 777,564, of December 13, 1904. The lower work-holder supporting bar of the machine which is adapted to be moved over the machine-bed by the usual feed-cams, has mounted upon it an article carrier or disk formed 65 in the present instance with a succession of article-receiving seats. This disk is adapted to present individual articles to the stitch-forming mechanism at the under side of the work; the article-supporting seats being 70 adapted to register successively with an upper presser or clamping member. Mounted at the under side of the disk is a spring and ratchet mechanism in which power received from the motion of the work-holder 75 during a sewing operation is stored. When the presser-foot is lifted to release the work, the disk is released and the power stored in the spring is used to turn the disk sufficiently 80 to present a new article to the stitch-forming mechanism. The articles may be placed in the article-receiving seats by hand at a station remote from the sewing station.

The invention includes various constructive features and combinations of parts hereinafter described and particularly pointed out in the appended claims.

In the accompanying drawings, Fig. 1 is a side elevation of a sewing machine embodying the invention. Fig. 2 is a top plan view of the machine; the bracket-arm being broken away and the standard being shown in horizontal section at the level of the main-shaft. Figs. 2^a and 2^b are, respectively, sections on the lines 2^a—2^a and 2^b—2^b, Fig. 2. 90 Fig. 2^c is a section on the line 2^c—2^c, Fig. 2. Fig. 3 is a bottom plan view of the machine. Fig. 4 is a transverse vertical section through the machine bed on the line 4—4. Fig. 1, showing in elevation the actuating mechanism for the article-supporting disk. Figs. 5 and 6 are sectional views of the disk-actuating mechanism, showing the locking lever for the work-supporting disk in locking and 95 100

releasing relation with the toothed hub of said disk. Fig. 7 is a vertical section on the line 7—7, Fig. 6. Fig. 8 is a vertical sectional view illustrating an expedient for adjusting the tension of the disk-actuating spring. Fig. 9 is a bottom plan view of the toothed hub-member for the work-supporting disk. Fig. 10 is a top plan view of the ratchet-wheel associated with the hub-member shown in Fig. 9. Fig. 11 is a sectional view on line 11—11, Fig. 2. Fig. 12 is a disassembled perspective view of the bearing pin and head piece which support the disk-actuating mechanism. Fig. 13 is a fragmentary bottom plan view of the disk-actuating mechanism with the parts in the positions which they occupy at the beginning of a sewing operation. Fig. 14 is a similar view illustrating the manner in which the actuating spring is wound up during the sewing of the first side of the label. Fig. 15 is a similar view illustrating the tripping of the winding pawl to prevent repeated winding of the spring in case the sewing on a given article is repeated. Fig. 16 is a similar view illustrating the tripping of the stopping latch to restore it to initial position. Fig. 17 is a view similar to Fig. 15 showing the action of the stopping latch when the locking lever is shifted to release the article-carrying disk. Fig. 18 is a detail perspective view of the locking lever and Fig. 19 is a view of an article or label such as the present machine is adapted to sew.

For the purposes of the present disclosure, the invention is illustrated as embodied in a machine of the type represented in said Sullivan patent. Such a machine comprises a bed 1, standard 2, and bracket-arm 3 terminating in a hollow head 4 in which reciprocates the needle-bar 5 carrying the eye-pointed needle 6; the latter cooperating as usual with a suitable loop-taker or shuttle 7 stationed below the bed in the raceway 8 and receiving motion from the loop-taker shaft 9. The machine is provided with the customary stop-motion device including the starting and stopping lever 10 which operates with a stopping cam 11 on the hub of a pulley 12 fixed to the main-shaft 13. Disposed alongside the pulley 12 is a loose pulley 14 which receives the driving belt when the lever 10 springs to stopping position. Geared to the main-shaft 13 is the usual pattern-wheel 15 having in its opposite faces the cam-groove 16, 17, which operate through the usual connections such as disclosed in said Sullivan patent to impart longitudinal and lateral components of feeding motion to the work-holder supporting bar 18. The longitudinal components of motion are derived from the cam-groove 16 which vibrates the lever 19 about its pivot 20; the lever 19 having a slotted arm 21 em-

bracing a vertically adjustable slide-block 22 on the post 23 rigidly mounted on the work-holder supporting bar 18. The lateral components of motion of the work-holder are derived from the cam-groove 17 which rocks the lever 24 about its pivot 25. The lever 24 is connected by means of a link 26 to the slotted arm 27 of a bellcrank-lever pivoted at 28 to the under side of the bed 1. The other arm 29 of the bellcrank-lever is connected by means of a link 30 to the plate-like extension 31 of the head-piece 32 rigidly secured to the head 33 of the bearing pin 34 by means of the screw 35; the head 33 being formed with a diametrical slot 33', Fig. 12, which receives the rib 32' of the head-piece 32.

The bearing pin 34 is formed at its upper end with a reduced portion 36, Fig. 5, which enters an aperture 37 in the forward free end of the work-holder supporting bar 18 and is rigidly secured in position by means of a nut 38 screwed into the further reduced and threaded extremity 39 of the pin 34. The work-holder supporting bar 18 swings about the axis of the post 23, Fig. 1, in performing its lateral components of motions.

The label-support is preferably made in the form of a circular disk 40, Fig. 2, rigidly secured to the seat 41, Figs. 5 and 6, on the hub member 42 by means of circumferentially spaced screws, one of which is shown at 43. The hub-member 42 is journaled for turning movement upon the pin 34 and is confined against end play by means of the head 33 of said pin and the extremity of the bar 18. The label-supporting disk 40 rests upon the flat upper surface of the bed 1 and is adapted to slide thereover in rigid relation with the bar 18 during the sewing operation.

Referring to Figs. 2, 2^a and 2^b, it will be seen that the disk 40 is formed near its edge with a succession of label-receiving cavities each of which comprises a rectangular aperture 44 in the disk 40. Extending along the sides and ends of the apertures 44, below the level of the upper surface of said disk, are the label-supporting ledges 45. Above the end-ledges are disposed the inwardly directed label-confining lips 46.

Rigidly mounted on the work-holder supporting bar 18, Fig. 1, is the base 47 of the work-holder bracket-arm 48 which terminates at its free end in a head 49 formed with a suitable internal slideway for the presser-bar 50 having at its lower end a presser-foot 51. A coil-spring 52 yieldingly presses the foot 51 toward the disk 40.

The presser-foot 51 comprises a frame formed with a rectangular aperture 53, Fig. 2, of substantially the same size as the apertures 44 in the disk 40. The presser-foot is further formed along the sides of the

aperture 53 with downwardly directed ribs 54, Fig. 2^c, which are adapted to clamp the fabric *f*, and the side edges of the label *p* tightly upon the label-supporting ledges 45. 5 The label cavities 44 are evenly spaced circumferentially of the disk 40 and are adapted to register successively with the presser-foot 51. It will be understood that the bar 18 and arm 48 constitute a carrier 10 frame including upper and lower carrier elements for the work-holder elements 40 and 51.

In the present machine, mechanism is provided for automatically advancing or turning 15 the disk 40 one step when the presser-foot is lifted thereby carrying a new label to sewing position. During a sewing operation the disk 40 is locked rigidly to the bar 18. When the presser-foot is lifted 20 after a sewing operation the disk is released and an actuating spring, in which power is stored during the sewing, turns the disk one step to carry a label to sewing position.

25 Referring to Figs. 4 to 10, inclusive, it will be seen that the hub-member 42 is formed with a flange 55 in which is cut a number of radial notches 56 equal to the number of label seats in the disk 40. The 30 head-piece 32 is formed with spaced ears 57 between which extends the pivot pin 58 for the escapement lever 59 one end of which is formed with an upwardly directed tooth 60 adapted to enter one of the notches 56 in the 35 flange of the hub-member 42 and lock the disk 40 against turning movement. The short coil-spring 61, Fig. 5, yieldingly maintains the lever 59 in locking engagement with the hub of the disk 40.

40 The hub-member 42, Fig. 7, is formed between the flange 56 and inner sleeve 62 with an annular cavity 63 which houses the coiled actuating spring 64. Journaled within the cavity 63 upon the sleeve 62 is the sleeve-like

45 hub 65 of a ratchet-wheel 66 which is formed with a number of ratchet teeth 67 equal to the number of label-seats in the disk 40. One end 68, Figs. 6 and 8, of the spring 64 is anchored in the hub-member 42 and the 50 other end 69 of said spring, Figs. 7 and 8, is anchored in an adjusting ring 70 which surrounds the hub 65 of the ratchet-wheel and is secured in adjusted position by means of a screw 71 passing through the arcuate slot 55 72, in the ratchet-wheel and threaded into the adjusting ring. The tension of the actuating spring 64 may be varied by turning the ring 70 relatively to the ratchet-wheel.

A spring-pressed holding pawl 73 mounted 60 on the plate-like extension 31 of the head-piece 32 is adapted to coact successively with the ratchet-teeth 67 to hold the actuating spring under tension, as will be more particularly described.

During the sewing of the first side of the 65 label, the work-holder moves sidewise from the position shown in Fig. 13 to that shown in Fig. 14. This motion is utilized to advance or turn the ratchet-wheel 66 one step and store power in the spring 64. Interposed in the path of a tooth 75, Fig. 13, of the ratchet-wheel during this side motion of the work-holder, is the extremity 76 of the winding pawl 77 which is pivoted at 78 to the bed 1. A spring 79 anchored at one end 75 to the pawl 77 and at its opposite end to a stationary hook 80 tends to withdraw the pawl 77 to inoperative position. The pawl 77, however, is held in its operative position by means of a spring-pressed latch 81 which is pivoted at 82 to the bed 1. The latch 81 is formed with a tail piece 83 and with a lateral hook 84 which engages a pin 85 on the angular extension 86 of the winding pawl 77. Mounted on the pawl 77 adjacent the pin 85 is a screw-pin 87 which is adapted to be struck by an element connected to the presser-foot lifting mechanism, to be described, to reset the pawl in its operative position after the latch 81 has been tripped. 90

It will be clear that as the work-holder moves laterally during the sewing of the first side of the label (Figs. 13 and 14) the extremity 76 of the winding pawl 77 will be struck by the tooth 75 and the continued 95 sidewise motion of the work-holder will cause the ratchet-wheel 66 to be turned relatively to the hub-member 42, thereby winding up or storing power in the actuating spring 64. Fig. 14 shows the holding-pawl 100 73 just on the point of dropping in behind the tooth 88 of the ratchet-wheel 66, which it will do prior to the completion of the stitching along the first side of the label. This 105 winding action restores to the spring 64 the power expended in turning the label-holding disk 40 one step between stitching operations.

During the sewing of the first end of the label, the latch 81 is stripped to release the 110 winding pawl 77, whereupon the spring 79 swings said pawl to its inoperative position. The tripping of the latch 81 is accomplished by means of the screw-pin 89 which is carried by the head-piece 32. As shown in 115 Figs. 14 and 15, the screw-pin 89 strikes the tail-piece 83 of the latch-lever 81 and swings the latter to the right sufficiently to withdraw the hook 84 from the pin 85. In its inoperative position, the pawl 77 rests 120 against the bearing lug 90 for the loop-taker shaft. The object of shifting the winding pawl 77 to inoperative position after it has performed its function is to prevent a repetition of the winding action in case the first 125 sewing is defective and it is desired to repeat the sewing operation on the same label. When the presser-foot 51 is lifted to release

the work, the winding pawl is reset in a manner to be explained.

In order to prevent the label-carrying disk 40 from being turned too far by its actuating spring 64, mechanism is provided for stopping said disk with the next label-seat in register with the presser-foot. Pivotally mounted at 91 on the escapement lever 59 is a bellcrank-lever, one arm 92 of which is formed with a circular head 93 adapted to fit snugly within a notch 56 in the flange of the hub-member 42. The other arm 94 of the bellcrank-lever carries a latch-pin 95 which is adapted to rest behind the lateral hook 96 on the latch-arm 97 pivoted at 98 to a lateral extension 99 on the lever 59. The latch 97 is pressed into holding engagement with the pin 95 by means of the coil spring 100. During the sewing operation, the bellcrank-lever 92-94 is sustained at a level below that of the toothed flange of the hub-member, as shown in Fig. 5. When the latch 97 is tripped, the bellcrank-lever 92, 94 is free to swing about its pivot 91 from the position shown in Fig. 15 to that shown in Fig. 16 under the influence of the light spring 100. This action advances the circular head 93 of the bellcrank-lever to a position such that it will be lifted into an adjacent notch 56 in the hub-member 42 when the escapement lever 59 is rocked to release the hub-member. During the sewing of the second side of the label, Fig. 16, the latch 97 is moved into engagement with the stationary stop 101 on the bed 1 and the continued motion of the work-holder causes said latch to be tripped by said stop, thereby releasing the bellcrank-lever 92, 94.

When the stitching is completed, the operator rocks the escapement lever 59 from the position shown in Fig. 5 to that shown in Fig. 6, and thereby lifts the circular head 93 of the bellcrank-lever 92, 94 into one of the notches 56 before the locking tooth 60 is withdrawn from another of said notches in the hub-member 42. As soon as the hub-member is released from the locking tooth 60, the relatively strong actuating spring 64 advances said hub-member one step, whereupon the motion of the arm 92 of the bellcrank-lever, Fig. 17, is arrested by the stopping lug 102. When the arm 92 strikes the stopping lug 102, the latch-pin 95 is caught by the hook 96 on the latch 97, thus preventing rebound of the hub-member 42 and effectively locking the latter until the locking tooth 60 is inserted in the next one of the notches 56 upon restoration of lever 59 to locking position by the spring 61.

The means for rocking the locking lever to release the disk 40 comprises a lever 103, Fig. 4, pivoted at 104 to a bracket-arm 105 depending from the bed 1. The lever 103 carries at its free end an adjustable contact screw 105' which is adapted to lift that arm

of the locking lever 59 which carries the bellcrank-lever 92, 94. The lever 103 is rocked by means of the treadle-controlled lever 106 pivoted at 107 to the bracket 108 sustained by the machine bed. One arm of the lever 106 extends under the lever 103 and the other arm is connected to the usual treadle or knee-shift by means of the chain 109. The lever 103 is formed with an upwardly and rearwardly curved extension 110 which is adapted to strike the pin 87 on the angular extension 86 of the winding pawl 77 and reset said pawl in operative position.

Connected to the lever 106 near the treadle-chain 109 is a presser-foot lifting chain 111 which is connected at its upper end to the usual presser-foot lifting lever 112 pivoted at 113 to the bracket-arm 3. The lever 112 is connected at its forward end to the vertical slide-rod 113' journaled in the head 4. This slide-rod carries at its lower end the angular extension piece 114 which is adapted to lift the lateral pin 115 carried by the presser-bar 50.

It will be understood from the foregoing disclosure that when the presser-foot is lifted, the label-carrying disk is released and turned one step to present a new label to sewing position. Repeated lifting of the presser-foot, however, will not cause or initiate further turning movement of the disk until the machine has passed through a sewing cycle.

The bed 1 carries adjustable stop-screws 116, 117, Fig. 3, adapted to be struck by the arms 27, 29, respectively, of the bellcrank-lever through which lateral motion is imparted to the work-holder. These stops prevent overthrow of the work-holder and insure that the needle will not strike the disk 105 at the ends of the label cavities.

The labels are preferably to be inserted in the label-cavities 44 at a filling station, Fig. 2, remote from the sewing station. Secured to the bar 48 by screws 118 is a shallow label-supply pan 119 to the inside bottom wall of which is secured the parallel guide-strips 120 which are spaced apart a distance equal to the width of a label and are substantially in register, widthwise, with the sides of the label-cavity at the filling station. Secured to one of the guide-strips 120 with its inner edge in overhanging relation with the inner edge of said strip is a retaining strip 121. To the other guide-strip is secured a guard-plate 122 which serves to prevent the work from getting into and obstructing the passageway 123 between the guide-strips 120.

Secured to the pan 119 and extending over the label-cavity at the end of the guideway 123 is a plate 124 having an upturned lip 124' which serves to deflect the label downwardly into a label-cavity 44. During a sewing operation, the operator pushes a label, 130

bottom side up, along the guideway 123 and into the label-cavity at the end of said guideway.

It will be appreciated that it would be a difficult matter for the operator, unassisted by the guideway 123, to place labels in label-cavities while the work-holder is moving over the bed of the machine. The guideway 123, associated with the moving work-holder, is therefore a feature of importance from a practical standpoint.

A guard-plate 125, secured under the nut 38, covers the filled label-cavities between the filling and sewing stations and prevents disarrangement of the labels in said cavities by accidental contact of the work therewith.

The machine is also equipped with a thread-cutter 126 which is preferably constructed substantially in accordance with the disclosure of said Sullivan patent.

While any sort of individual articles, patches or labels, may be sewn on the present machine, the carrier herein shown and described is particularly adapted to accommodate labels having previously folded side edges 127 and end edges 128, as shown in Fig. 19, such labels being well known to the trade.

Having thus set forth the nature of the invention, what I claim herein is:—

1. A label sewing machine having, in combination, stitch-forming mechanism, a stop-motion device for governing its period of action, means for automatically feeding labels to sewing position at the under side of the work, a presser member at the upper side of the work, and means for relatively moving the stitch-forming mechanism and label to sew around the margin of the latter.

40 2. A label sewing machine having, in combination, stitch-forming mechanism, a stop-motion device for governing its period of action, spring-operated means for feeding labels to sewing position at the under side of the work, a presser-member at the upper side of the work, means for relatively moving the stitch-forming mechanism and label to sew the label to the under side of the work, and means acting during the sewing to store power in said spring.

50 3. A label sewing machine having, in combination, stitch-forming mechanism, a stop-motion device for governing its period of action, means including a revoluble label-carrying disk below the work for automatically feeding labels to sewing position at the under side of the work, a presser member at the upper side of the work, and means for relatively moving the stitch-forming mechanism and label to sew around the margin of the latter.

4. An article-attaching sewing machine having, in combination, stitch-forming mechanism, a stop-motion device for governing its period of action, means for supporting

an article at the under side of the work during the sewing, presser means above the work, and means governed by the presser-foot lifting mechanism for presenting a new article to the stitch-forming mechanism.

70

5. A label sewing machine having, in combination, stitch-forming mechanism, a stop-motion device for governing its period of action, a work-holder, means for relatively moving the stitch-forming mechanism and work-holder to sew around a label, said work-holder including a circular disk formed with a succession of label-supporting seats, and means for turning said disk after a sewing operation to locate a new label in sewing position.

75

6. A label sewing machine having, in combination, stitch-forming mechanism, a stop-motion device for governing its period of action, a work-holder, means for relatively moving the stitch-forming mechanism and work-holder to sew around a label, said work-holder including a circular disk formed with a succession of label-seats adapted to present labels successively to the stitch-forming mechanism at the under side of the work, and means for turning said disk after a sewing operation to locate a new label in sewing position below the work.

85

7. An article-attaching machine having, in combination, fastening inserting mechanism, means including an article engaging element and an actuating spring for feeding articles to fastening position, and means acting on said spring independently of said article engaging element during the fastening inserting operation to store power in said spring.

90

8. An article attaching machine having, in combination, fastener-inserting mechanism, an article-engaging element, means including an actuating spring for moving said article-engaging element to feed an article to attaching position, and means acting during the fastening operation to store power in said spring without reversing the motion of said article-engaging element.

100

9. An article attaching machine having, in combination, fastener-inserting mechanism, an article-engaging element, means including an actuating spring connected at one end to said article-engaging element and acting to cause said element to feed an article to attaching position, and means acting on the other end of said spring independently of said article-engaging element and during the fastening operation to store power in said spring.

110

10. An article-attaching machine having, in combination, stitch-forming mechanism, a stop-motion device for governing its period of action, a work-holder, means for relatively moving the stitch-forming mechanism and work-holder to attach an article, said work-holder including an article holder formed

125

115 130

with a succession of article-receiving seats, an actuating spring for said holder, means acting during the sewing to store power in said spring, and a trip for releasing said holder to permit it to be shifted by said spring sufficiently to present a new article to the stitch-forming mechanism.

11. An article-attaching machine having, in combination, stitch-forming mechanism, a stop-motion device for governing its period of action, a work-holder, means for relatively moving the stitch-forming mechanism and work-holder to attach an article, said work-holder including a lower work-supporting disk formed with a succession of article-supporting seats and an upper presser member for clamping the work upon said disk during the sewing, means for turning said disk after a sewing operation to locate a new article in sewing position, and a stop for arresting the turning motion of said disk when the new article reaches sewing position.

12. A label sewing machine having, in combination, stitch-forming mechanism, a stop-motion device for governing its period of action, a work-holder, means for relatively moving the stitch-forming mechanism and work-holder to sew around a label, said work-holder including a lower work-supporting disk formed with a succession of label-receiving seats and an upper presser member for clamping the work upon said disk during the sewing, presser-foot lifting mechanism, and means governed by said presser-foot lifting mechanism for turning said disk to carry a new label to sewing position.

13. An article-sewing machine having, in combination, stitch-forming mechanism, a stop-motion device for governing its period of action, a work-holder, means for relatively moving the stitch-forming mechanism and work-holder to attach an article, said work-holder including a circular disk formed with a succession of article-receiving seats including article-supporting ledges below the level of the upper surface of said disk, a presser member having downwardly directed projections adapted to clamp an article and the superposed work against said ledges, and means for turning said disk after a sewing operation to present a new article to the stitch-forming mechanism.

14. A sewing machine having in combination, stitch-forming mechanism, a work-holder comprising a circular disk formed with a succession of article-receiving seats and a presser-foot adapted to register successively with said seats, means for producing relative stitch-positioning movements between said stitch-forming mechanism and work-holder, a spring adapted to turn said disk between sewing periods, means for storing power in said spring, a latch for hold-

ing said disk against turning movement during the sewing, a presser-foot lifter, and means connected with the presser-foot lifter for tripping said latch.

15. A work-holder for label sewing machines comprising, a carrier, and a label-holder movably mounted on said carrier and formed with a succession of label-receiving seats, each of said seats including lower label-supporting ledges and upper lips adapted to overhang a label resting upon said ledges.

16. A work-holder for article-attaching machines comprising, a carrier, an article-holder movably mounted on said carrier and formed with a succession of article-receiving seats including article-supporting ledges, and a presser-member adapted to register successively with said seats and clamp the articles against said ledges.

17. A label sewing machine having, in combination, stitch-forming mechanism, a work-holder including a lower circular disk formed with a succession of label-receiving seats adapted to present the labels successively to the stitch-forming mechanism at the under side of the work, and an upper presser member with means for lifting it to release the work between label-stitching operations.

18. A work-holder for article-attaching sewing machines comprising a carrier-frame adapted for movement over the bed of a sewing machine and including upper and lower carrier members, a revoluble article carrying disk pivotally mounted on said lower carrier member and formed with a succession of article-receiving seats, and a presser member sustained by said upper carrier member and adapted to press the work upon an article sustained by said lower carrier member.

19. A work-holder for article-attaching machines comprising rigidly associated supporting and overhanging bracket arms, an article-carrying disk mounted for turning movement on the supporting arm and formed with a succession of article-receiving cavities, and a clamping foot mounted upon the bracket arm for movement toward and from said disk.

20. A work-holder for article-attaching machines comprising, in combination, an article-carrying disk having a succession of article-receiving cavities and formed with a notched hub, a locking element cooperating with said notched hub to lock said disk during the attaching operation, a ratchet-wheel associated with said notched hub, an actuating spring anchored to said hub and ratchet-wheel, means acting on said ratchet-wheel during the attaching operation to store power in said spring, and means acting on said locking element after the attaching operation to release said disk and

permit said spring to turn it sufficiently to carry a new article to attaching position.

21. A work-holder for label-sewing machines comprising, in combination, a label-supporting disk formed with a succession of label-seats and with a notched hub, a locking element cooperating with said notched hub to lock said disk during the sewing operation, a ratchet-wheel associated with said hub, an actuating spring connecting said hub and wheel, means for turning said wheel during the sewing to store power in said spring, a presser-foot, a presser-foot lifter, and means connected to said presser-foot lifter for unlocking said disk and permitting said spring to turn the latter.

22. A work-holder for article-attaching machines having, in combination, an article-carrying disk having a succession of article-receiving cavities and a notched hub, a pivoted locking lever carrying locking and stopping elements at opposite sides of its pivot adapted to cooperate alternately with said hub, and means for rocking said lever.

23. A work-holder for article-attaching machines having, in combination, an article-carrying disk having a succession of article-receiving cavities, an actuating spring applied to said disk, and a toothed wheel escapement device for permitting step-by-step turning movements of said disk under the influence of its actuating spring.

24. An article-attaching machine having, in combination, a frame, stitch-forming mechanism, a work-holder movable relatively to the frame and stitch-forming mechanism during the sewing, said work-holder including a support and an article-carrying disk pivotally carried by said support and formed with a succession of article-receiving cavities, means for turning said disk between sewing operations, and guiding means mounted on said support for assisting the operator in placing the articles by hand in the article-receiving cavities.

25. An article-attaching machine having, in combination, a frame, stitch-forming mechanism, a work-holder movable relatively to the frame and stitch-forming mechanism during the sewing, said work-holder including a support and an article-carrying disk pivotally carried by said support and formed with a succession of article-receiving cavities, means for turning said disk between sewing operations, and a horizontally disposed guideway mounted on said support and leading to an article-receiving cavity removed from the sewing station.

26. An article-attaching machine having, in combination, a frame, stitch-forming mechanism, a work-holder movable relatively to the frame and stitch-forming mechanism during the sewing, said work-holder including a support and an article-carrying disk pivotally carried by said support and formed with a succession of article-receiving cavities, means for turning said disk between sewing operations, a horizontally disposed guideway mounted on said support and leading to an article receiving cavity removed from the sewing station, and a deflector at the end of said guideway for directing the articles downwardly into the article-receiving cavities.

27. In a label sewing machine, in combination, stitch-forming mechanism, a label-carrying disk formed with a succession of label-receiving cavities, means for moving said disk relatively to the stitch-forming mechanism to sew around the margin of the label, a label supply pan moving with said disk during the sewing and formed with a substantially horizontally disposed label guideway leading to a label-cavity removed from the sewing station.

In testimony whereof, I have signed my name to this specification.

ALFRED GRIEB.
